UNITED STATES PATENT OFFICE.

JOHN D. CAMBLIN, OF FULTON, INDIANA.

PISTON-RING HOLDER.

Application filed December 20, 1924. Serial No. 757,270.

This invention relates to improvements in tools especially designed for holding piston rings, whereby the rings may be conveniently and accurately fitted.

An object of the present invention is to provide a tool for this purpose which will accommodate rings of different sizes and by means of which the ends of the rings may be held in proper relative position for filing and the operation accomplished in a manner to insure proper parallelism for the opposed faces of the ring ends.

With the above and other objects in view, the invention further includes the following novel features and details of construction, to be hereinafter more fully described, illustrated in the accompanying drawings and pointed out in the appended claims.

In the drawings:—

Figure 1 is an elevation illustrating the tool in use.

Figure 2 is a top plan view of the same showing the position of a file when a ring is being fitted.

Figure 3 is a longitudinal sectional view.

Figure 4 is a detail perspective view of the slidable gripping jaw.

Figure 5 is an enlarged sectional view on the line 5—5 of Figure 2.

Figure 6 is a view similar to Figure 1 but looking at the reverse side of the tool with the latter adjusted to accommodate a ring of relatively small diameter.

Figure 7 is an enlarged sectional view taken substantially on the line 7—7 of Figure 6.

Referring in detail to the drawings where-in like characters of reference denote corresponding parts, the tool as illustrated comprises a plurality of spaced pairs of divergent arms 10. Each pair of arms is connected at one end as indicated at 11 and provide a substantially V-shaped member.

Each pair of arms is spaced apart to provide ring receiving grooves 12 and for this purpose the free ends of the arms 10 have secured between them spacing blocks 13, the latter acting to space the arms apart and form end walls for the grooves 12. The blocks are secured in place by means of rivets or pins 14.

The opposite ends of the arms 10 are connected by a pin 15 and mounted upon this pin between two of the arms 10 is a spacing block 16. Slidingly mounted within the slots 12 adjacent the block 16 is a

slidable gripping jaw which comprises a substantially H-shaped head 17. The lugs 18 which extend from this head are slideable in the slots 12 while the notch 19 between the lugs 18 receives the intermediate arm 10. Extending from the head 17 is an arm 20 which is provided with a longitudinal slot 21. This slot receives the pin 15 and the latter acts to limit sliding movement of the head 17. The arm 20 is located at one side of the head 17 and provides space for an eccentric 22 which is mounted for pivotal movement upon the pin 15; a handle 23 which extends from this eccentric provides convenient means for its operation.

In the use of the tool as shown in Figures 1 and 2 of the drawings, a piston ring P is placed within one of the slots 12 with the periphery of the ring engaging spacing blocks 13 at the outer ends of the slots. The eccentric 22 is then operated to force the head 17 against the ring, the said eccentric bearing against the head so that the latter will be forced inward and the ring compressed. If the ends of the ring do not properly align, release the pressure and rotate the ring within the tool until proper alignment is obtained. Then the ring may be released sufficiently to permit of the insertion of a file F between the ends of the ring and the file manipulated for the removal of sufficient material to provide a proper fit. By this means both ends of the ring may be filed simultaneously and accurate parallelism of the opposed faces of the ring ends insured.

The tool is capable of holding rings of different sizes and for this purpose the slots 12 are of a different width. In addition, the arms 10 are provided adjacent their outer ends with spaced openings 24 which accommodate cotter or other pins 25. These pins when inserted in the proper openings provided abutments against which the ring may be raised as illustrated in Figure 6 of the drawings. The ring may then be compressed in the manner previously described.

The invention is susceptible of various changes in its form, proportions and minor details of construction and the right is herein reserved to make such changes as properly fall within the scope of the appended claims.

Having described the invention what is claimed is:—

1. A tool of the class described including

a plurality of pairs of divergent arms of substantially V-shaped formation and arranged in spaced relation to provide spaced slots adapted to receive piston rings, spacing blocks between the ends of the arms, a pin connecting the opposite ends of the arms, a 5 slidable member located in one end of the slots to engage and force the rings into contact with the opposite end walls of the slots and compress the rings and means whereby the slidable member may be operated.

2. A tool of the class described including a plurality of pairs of divergent arms of substantially V-shaped formation and arranged in spaced relation to provide spaced 15 slots adapted to receive piston rings, spacing blocks between the ends of the arms, a pin connecting the opposite ends of the arms, a slidable member located in one end 20 of the slots to engage and force the rings into contact with the opposite end walls of

the slots and compress the rings, an eccentric on the pin and a lever on the eccentric whereby to actuate said slidable member.

3. A tool of the class described comprising a plurality of pairs of divergent arms of substantially V-shaped formation and arranged in spaced relation to provide spaced slots adapted to receive piston rings, a slidable member including a substantially H-shaped head adapted to engage and force the rings into contact with the opposite end walls of the slots and compress the rings, a slotted arm extending from the head, a guide pin carried by the divergent arms and 35 extending through the slotted arm and an eccentric mounted upon the guide pin for engagement with the head whereby the slidable member may be operated.

In testimony whereof I affix my signature.

JOHN D. CAMBLIN.
